UNITED STATES PATENT OFFICE.

JOHN H. PAALMAN, OF GRAND RAPIDS, MICHIGAN.

SERVING TABLE.

Application filed August 6, 1923. Serial No. 656,014.

To all whom it may concern:

Be it known that I, JOHN H. PAALMAN, a citizen of the United States, residing at Grand Rapids, county of Kent, State of Michigan, have invented certain new and useful Improvements in Serving Tables, of which the following is a specification.

This invention relates to improvements in serving tables.

10 The main object of this invention is to provide an improved serving table in which the handle may be collapsed or swung below the top when desired, as for using the table for a luncheon table or for other purposes where the handle is not desired.

Objects pertaining to details and economies of construction and operation will definitely appear from the detailed description to follow.

20 I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a side elevation of a serving table embodying the features of my invention.

Fig. II is a fragmentary end elevation looking from the right of Fig. I.

Fig. III is a vertical section on a line corresponding to line 3—3 of Fig. II, looking in the direction of the arrows.

In the drawing the similar numerals of reference indicate similar parts in all of the views.

Referring to the drawing, the legs or corner uprights 1 are connected by the side rails 2, the top 3 being mounted upon these uprights and side rails. The shelf 4 at the lower ends of the uprights also constitutes a frame member. The caster wheels 5 are secured to the rear uprights while the axle of the front wheels 6 is secured to the shelf 4.

I provide a handle consisting of the arms 7 which are curved upwardly at their outer ends, the spindle-like handpiece 8 being secured to their outer ends. A cross-piece 9 connects the arms 7 adjacent their inner ends, their inner ends projecting at 10 beyond the cross piece to provide pivot arms which are pivoted to the inner sides of the

side rails by the pivots 11. The arms are 55 supported with their outer sides in bearing or swinging engagement with the side rails, the handle as a whole being rigid, although pivotally mounted, and it constitutes a supporting member or brace member for the 60 frame.

The cross piece and arms are arranged in relation with the pivot 11, or vice versa, so that when the handle is erected the upper edges of the arms and the cross piece lie 65 against the under side of the table top.

A spring latch 12 is secured to the under side of the table top and is provided with an opening 13 to engage the pin 14 on the cross piece, the outer end of this latch being offset so that it forms an inclined strike for the pin as the handle is swung to erected position, and also to provide an outwardly projecting finger piece which may be 70 grasped to release the handle. 75

With this arrangement of parts I provide a structure which is very simple and economical in its parts, is strong and rigid and neat and attractive in appearance.

Having thus described my invention what 80 I claim as new and desire to secure by Letters Patent is:

1. In a serving table, the combination of corner uprights, side rails connecting said uprights, a top secured upon said side rails 85 and uprights, a handle comprising a pair of arms pivoted on the inner sides of said side rails to swing downwardly between the adjacent pair of uprights or to swing to erected position with their upper edges 90 against the under sides of said top, a cross piece disposed between said arms so that its upper edge engages the under side of the table top when the arms are in erected position, a handpiece carried by said arms, and a spring latch mounted on the under side of said table top and having an inclined outer end with an opening at the base thereof, said cross piece being provided with a pin adapted to automatically engage said opening when the arms are swung to erected position. 100

2. In a serving table, the combination of corner uprights, side rails connecting said uprights, a top secured upon said side rails 105 and uprights, a handle comprising a pair of supporting arms having a handpiece at their outer ends and a cross piece adjacent their

inner ends, said supporting arms being pivoted on the inner sides of said side rails to swing against the under side of the table top or to be collapsed between the adjacent uprights, a pin on said cross piece, and a spring catch mounted on the under side of the table adapted to automatically engage said pin

when the handle is swung to erected position, the outer end of said latch being offset to provide a fingerpiece for releasing the latch.

In witness whereof, I have hereunto set my hand.

JOHN H. PAALMAN. [L.S.]
